(57) **CLAIM**

The ornamental design for an adjustable hooded jacket, as
shown and described.

DESCRIPTION

FIG. 1 is a perspective front view of an adjustable hooded
jacket with a zipper on a front of the jacket and a zipper on a
hood of the jacket according to the present invention;

FIG. 2 is a perspective front view of the adjustable hooded
jacket of FIG. 1 with the hood in a wearing position;

FIG. 3 is a perspective front view of the adjustable hooded
jacket of FIG. 1 with the hood lying in an unzipped and open
position;

FIG. 4 is a perspective rear view of the adjustable hooded
jacket in the unzipped and open position of FIG. 3;

FIG. 5 is a perspective rear view of the adjustable hooded
jacket of FIG. 1 with the hood lying in a zipped and closed
position;

FIG. 6 is an elevational right-side view of the adjustable
hooded jacket in the wearing position of FIG. 2;

FIG. 7 is an elevational left-side view of the adjustable
hooded jacket in the wearing position of FIG. 2;

FIG. 8 is a perspective front view of another exemplary
embodiment of an adjustable hooded jacket in accordance
with the present invention;

FIG. 9 is a perspective view of the adjustable hooded jacket of
FIG. 8 with the hood in a wearing position;

FIG. 10 is a perspective rear view of the adjustable hooded
jacket of FIG. 8;

FIG. 11 is an elevational right-side view of the adjustable
hooded jacket in the wearing position of FIG. 9; and,

FIG. 12 is an elevational left-side view of the adjustable
hooded jacket in the wearing position of FIG. 9.

The broken line showing of an image of a user is included for
the purpose of illustrating environmental structure and forms
no part of the claimed design.
